UNITED STATES PATENT OFFICE.

ERNEST L. TEICH, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

LOCK.

Application filed January 25, 1922. Serial No. 531,586.

To all whom it may concern:

Be it known that I, ERNEST L. TEICH, a citizen of the United States, residing at New Britain, county of Hartford, State of Connecticut, have invented a certain new and useful Improvement in Locks, of which the following is a full, clear, and exact description.

The present invention relates to locks and has special reference to so called office door locks.

The object of the invention is to improve the construction and mode of operation of locks of this character as will hereinafter appear.

A more specific object of the invention is to provide a lock of the type employing a night-latch, with means whereby when the night-latch is once set to block the outer knob it cannot be released again without the use of a master key or a key other than the pass key.

With the above objects in view the features of the invention consist in certain constructions, arrangements, and combinations of parts hereinafter described and claimed, the advantages of which will be obvious to those skilled in the art.

The several features of the invention will be clearly understood from the following description and accompanying drawings, in which—

Figure 1 is a side elevation of an office door lock, with the cover or cap-plate 35 of the lock case removed, embodying the features of the invention in their preferred form;

Fig. 2 is a vertical sectional view, partly in elevation, taken on the line 2—2 of Fig. 1;

Fig. 3 is a horizontal sectional view, partly in elevation, taken on the line 3—3 of Fig. 1;

Fig. 4 is a detail longitudinal sectional view of the locking cylinder showing the position of the pin tumblers when operated by the master key;

Fig. 5 is a similar view showing the position of the pin tumblers when operated by one of the ordinary pass keys;

Fig. 6 is a view similar to Fig. 1 but showing a portion of the door casing and door in which the lock is mounted, and showing in full lines the position of com-

ponent parts of the lock mechanism as they are being operated by the master key, and by broken lines the position of the parts as they are being operated by the ordinary pass key;

Fig. 7 is an elevation of the inner end of the locking cylinder but showing one of the cam or roll-back arms of the lock of a modified form;

Figs. 8 and 9 are detail side and bottom plan views of a component part of the lock mechanism; and

Figs. 10 and 11 are similar views of another component part of the lock mechanism.

The lock is illustrated in Fig. 6 of the drawings as being mounted in a door 2 having a door casing 4 which is provided with a striker or latch plate 6. The lock is provided with a casing 8 having a face plate 10 and a cover or cap-plate 12. The lock mechanism comprises a spring projected latch bolt 14 having a head 16, a stem 18 and a tail-piece 20. The lock mechanism is also provided with a locking cylinder 22 in which is mounted a key plug 24 and a downwardly spring pressed pin tumblers 26. The inner end of the key plug 24 carries a cam or roll-back arm 28, which, when the proper key is inserted in the plug and the plug is turned, may act on the tail-piece 20 to retract the latch bolt 14. A dead locking mechanism is provided for the latch bolt, which mechanism comprises a lever 30 pivotally mounted on a pin 32 secured to the casing, which is urged in a clockwise direction, viewing Fig. 6, by a spring 34. The dead locking lever 30 is provided with an arm 36 which when the door is locked closed, is positioned adjacent the back of the head 16 of the latch bolt so as to serve as an abutment to prevent the latch bolt from being forced back. In order that the dead locking lever 30 shall not interfere with the retraction of the latch bolt when the roll-back arm 28 is operated, a lever 38 is interposed between the dead locking lever 30 and the roll-back arm 28 of the cylinder lock and is so arranged that when the roll-back arm is actuated to retract the latch bolt the arm will act through the lever 38 to tilt the dead locking lever 30 out of the path of movement of the head of the latch bolt and this will occur just before the roll-

back arm engages the tail-piece of the bolt to retract the bolt. The actuating lever 38 is pivotally mounted on a stud 40 secured to the lock case and is provided with a 5 shouldered projection 42 adapted to be engaged by the roll-back arm of the cylinder lock, and with a projection 44 engaging a cam surface 46 on an upwardly extending arm 48 of the dead locking lever 30. The 10 lever 38 is urged in a clockwise direction by the spring 34 having its rear end secured to the lever. When the door is open the dead locking lever 30 is held out of the path of movement of the head of the latch bolt by 15 the engagement of the upright arm 48 of the lever with a downwardly projecting lug 50 on an outwardly sprung pressed auxiliary latch bolt 52. When the door is closed the auxiliary latch bolt 52 is retracted by the 20 engagement of the forward end thereof with the latch plate 6 of the door casing so as to enable the dead locking lever 30 to be returned by its spring into effective position behind the head of the latch bolt. 25 The lock is also provided with the usual independent knob spindles for independent operation of the latch bolt by means of the outer and inner knobs (not shown) respectively. The outer knob spindle is adapted 30 to operate a roll-back 54 to swing a roll-back lever 56 rearwardly which causes the upper end of the lever 56 to act on the tail-piece 20 to retract the bolt. The inner knob spindle is connected with a roll-back 58 lying immediately beneath the roll-back 54 and is also adapted to operate the latch operating lever 56 to retract the latch bolt. 35 A night latch is provided for blocking the roll-back 54 and, consequently, the outer 40 knob against operation. This night latch comprises two press pins 59 and 60 that are connected to operate simultaneously in opposite directions by means of a walking beam 62. The inner end of the press pin 59 45 is provided with a dog 64 adapted to engage a notch 66 in the roll-back 54 when the press pin 59 is depressed and to be released therefrom when the pin 60 is depressed. 50 Except as hereinafter described, the parts above referred to of the lock mechanism are substantially of a well known construction. Such prior construction, however, is objectionable in certain cases as it has been found 55 possible by means of a suitable implement inserted between the face plate of the lock and the door jamb, when the door is locked, to depress the night latch pin 60 and thus release the night latch from the roll-back 60 54, permitting the door to be opened by means of the outer knob. To overcome this objection it has been proposed heretofore to provide cooperating lugs on the dead locking lever 30 and the night latch pin 59 65 which are arranged to engage to block or dead lock the night latch upon the dead locking lever being tilted into position to dead lock the latch bolt as above described when the night latch is set to block the outer knob, and which are disengaged to 70 release the night latch when the dead locking lever 30 is tilted by means of the key to release the latch bolt upon opening the door. This construction, however, has also been found to be objectionable in certain 75 cases, for the reason that after the night watchman in making his rounds has tried the door and found it locked a person might thereafter release the night latch and inadvertently leave the door unlocked for the 80 remainder of the night. To overcome this objection as well as the objection to the first construction above described, the mechanism illustrated in the drawings is provided with means whereby when the night latch is once 85 set to block the outer knob, it cannot be released again without the use of a master key or a key other than the pass key. The construction is such, however, that a person may at any time open the door from the 90 inside by means of the inner knob and from the outside by means of the pass key. As shown, the night latch pin 59 is provided with an upstanding lug 68, which when the night latch is set to block the outer knob, 95 is positioned back of the end of a rearwardly projecting lug 70 on the dead locking lever 30. The lugs 68 and 70 correspond to said cooperating lugs of said prior construction above described except that in the present 100 construction the upstanding lug 68 is of sufficient length so that the lug 70 will not be carried out of engagement with the lug 68 when the dead locking lever 30 is tilted by the action of the roll-back 54 during the unlocking of the door by the pass key or by the auxiliary latch bolt 52 when the door is open. To enable the night latch to be released from the roll-back 54 the dead locking lever 30 must be tilted a sufficient 105 distance to disengage the lugs 68 and 70 and this is accomplished by means of a cam or roll-back arm 72 on the cylinder lock which is of sufficient length to act through the lever 38 to tilt the dead locking lever 30 the required distance. As shown the roll-back arm 72 is only capable of being operated by means of a master key 74. To provide for this the roll-back arm 72 is secured to the inner end of a sleeve 110 76 surrounding the key plug 24 and the pin tumblers 26 are such that when the pass key is inserted in the lock and turned the sleeve 76 is held stationary, and when the master key is inserted in the lock and turned the sleeve 76 turns with the key plug 24. In the construction illustrated in Fig. 6 of the drawings when the master key is used the roll-back arm 72 first engages the actuating lever 38 to release the dead locking 115 120 125 130

lever 30 from the latch bolt and night latch and while the roll-back is in engagement with the lever 38 it engages the tail-piece of the latch bolt to retract the bolt, but during 5 the continued movement of the roll back 72 to complete the retraction of the latch bolt the roll-back passes by the shouldered projection 42 of the actuating lever 38, so that with this construction it is necessary after 10 the door is opened to turn the roll-back 72 back into engagement with the shouldered projection 42 before the night latch can be released. In the construction illustrated in Fig. 7, however, the circumferential length 15 of the end of the roll-back 72' is sufficient to cause it to remain in engagement with the lug 42 during the complete retraction of the latch bolt and, hence, with this construction the night latch may be released while 20 the roll-back arm 72' is held at the limit of its effective movement.

It may be noted that when the night latch has been released the lug 68 is positioned beneath the lug 70 so that when in this position, 25 the lug 68 by engagement with the underside of the lug 70 prevents the dead locking lever 30 from being turned by its spring into position to dead lock the latch bolt and that the night latch, when released or in 30 "off" position, can be moved to "on" position without the use of the master key.

While it is preferred to employ the specific construction and arrangement of parts illustrated and described, it is to be understood 35 that this construction and arrangement is not essential except so far as specified in the claims and may be changed or modified without departing from the broader features of the invention.

40 What I claim is:-

1. A lock of the class described having, in combination, a latch bolt, a knob operable device for retracting the bolt, controllable mechanism for rendering said device operative and inoperative, dead locking means for preventing effective operation of said mechanism when said device has been rendered inoperative thereby, and means operable by one of a plurality of keys to retract 45 the latch bolt without releasing said dead locking means from said mechanism and operable by another of the keys to both retract the latch bolt and to release said dead locking means from said mechanism.

55 2. A lock of the class described having, in combination, a latch bolt, a knob operable device for retracting the bolt, controllable mechanism for rendering said device operative and inoperative, dead locking means 60 for preventing effective operation of said mechanism when said device has been rendered inoperative thereby and for preventing retraction of the latch bolt when the door is closed, and means operable by one of 65 a plurality of keys to release said dead lock-

ing means from the latch bolt without releasing it from said mechanism and operable by another key to release the dead locking means from both the latch bolt and said mechanism.

70 3. A lock of the class described having, in combination, a latch bolt, a knob operable device for retracting the bolt, controllable mechanism for rendering said device operative and inoperative, dead locking means 75 for preventing effective operation of said mechanism when said device has been rendered inoperative, and means operable by one of a plurality of keys to retract the latch bolt without releasing the dead locking means from said mechanism and operable by another of the keys to release the dead locking means from said mechanism.

80 4. A lock of the class described having, in combination, a latch bolt, a knob operable 85 device for retracting the bolt, controllable mechanism for rendering said device operative and inoperative, dead locking means for preventing retraction of the bolt when the door is closed, and for preventing effective 90 operation of said mechanism when said device is rendered inoperative thereby, and means operable by one of a plurality of keys to release said dead locking means from the latch bolt without releasing it from said 95 mechanism and operable by another of the keys to release said dead locking means from said mechanism.

100 5. A lock of the class described having, in combination, a latch bolt, a knob operable 105 device for retracting the bolt, controllable mechanism for rendering said device operative and inoperative, means comprising a pivotally mounted dead locking member capable of being tilted in one direction to prevent retraction of the bolt when the door is closed and to prevent operation of said mechanism when said device has been rendered inoperative thereby and capable of being tilted in the opposite direction a predetermined number of degrees to release the latch bolt alone and to be further tilted in the same direction to release said mechanism, and means operable by one of a plurality 110 of keys to tilt the dead locking member said predetermined number of degrees to release the latch bolt and capable of being operated by another of the keys to further tilt the dead locking member to release said mechanism.

115 6. A lock of the class described having, in combination, a lock case having a face-plate, a latch bolt extending through the face-plate, a knob operable device for retracting the latch bolt, a night latch for rendering 125 said device operative and inoperative comprising an operating pin extending through the face-plate, means for blocking said night latch when said device has been rendered inoperative, and means capable of being op- 130

erated from the exterior of a side of the lock case either to release said blocking means from the night latch and retract the latch bolt, or to retract the latch bolt without releasing said blocking means from the night latch.

7. A lock of the class described having, in combination, a latch bolt, a knob operable device for retracting the bolt, controllable mechanism for rendering said device operative and inoperative, dead locking means for preventing effective operation of said mechanism when said device has been rendered inoperative, and key operated means under the control of the operator either to release said dead locking means from said mechanism and to retract the latch bolt, or to retract the latch bolt without releasing said dead locking means from said mechanism.

8. A lock of the class described having, in combination, a latch bolt, a knob operable device for retracting the bolt, controllable mechanism for rendering said device operative and inoperative, dead locking means for preventing effective operation of said mechanism when said device has been rendered inoperative, and means comprising a key operated cam for retracting the latch bolt without releasing the dead locking means from said mechanism, and a second key operated cam for releasing the dead locking means from said mechanism, said cams being operated by separate keys.

9. A lock of the class described having, in combination, a latch bolt, a knob operable

device for retracting the bolt, controllable mechanism for rendering said device operative and inoperative, dead locking means for preventing retraction of the bolt when the door is closed and for preventing effective operation of said mechanism when said device is rendered inoperative thereby, and means operable by one of a plurality of keys for releasing the dead locking means from the latch bolt, for retracting the bolt and for releasing the dead locking means from said mechanism, and operable by another of the keys to release the dead locking means from the latch bolt and to retract the latch bolt without releasing the dead locking means from said mechanism.

10. A lock of the class described having, in combination, a latch bolt, a knob operable device for retracting the bolt, controllable mechanism for rendering said device operative and inoperative, dead locking means for preventing retraction of the bolt when the door is closed and for preventing effective operation of said mechanism when said device is rendered inoperative thereby, means acting upon opening the door to release the dead locking means from the latch bolt without releasing the dead locking means from said mechanism, and key operable means for releasing the dead locking means from the latch bolt, for retracting the latch bolt and for releasing the dead locking means from said mechanism.

ERNEST L. TEICH.
